(57) **CLAIM**

The ornamental design for a flexible light panel, as shown and described.

DESCRIPTION

FIG. 1 is a front elevation view of a flexible light panel. FIG. 2 is a front elevation view of the flexible light panel of FIG. 1 but with the enclosing edges shown in a non-enclosed condition.

FIG. 3 is a back elevation view of the flexible light panel of FIG. 2.

FIG. 4 is a close-up view of a portion of the flexible light panel of

FIG. 5 is a close-up view of a portion of the flexible light panel of FIG. 1 but with the enclosing edge shown in a non-enclosed condition with an electrical supply connector shown in phantom.

FIG. 6 is a view similar to that shown in FIG. 5 but with the enclosing edge shown in an enclosed condition with the electrical supply connector visible.

FIG. 7 is a sectional view of a flexible light panel, with the light emitting semiconductor strips removed, showing pockets formed when the holding panel is attached to the base panel.

FIG. 8 is a view similar to that shown in FIG. 7 but with light emitting semiconductor strips positioned within the pockets.

FIG. 9 is a view similar to that shown in FIG. 4 but with ends of light emitting semiconductor strips visible.

FIG. 10 shows the flexible light panel of FIG. 1 being

configured into a roll shape.

FIG. 11 shows the flexible light panel of FIG. 1 configured

into a roll shape.

FIG. 12 is a back elevation view of a flexible light panel engaged to a lighting apparatus holding device; and,

FIG. 13 is a front elevation view of a pair of flexible light

panels engaged to a lighting apparatus holding device.

(Continued)

The broken lines illustrate the environment in which the article embodying the design may be used and form no part of the claimed design.
